BEDSPRING

Isidore Zimet, Brooklyn, N. Y.

Application March 14, 1936, Serial No. 68,859

1 Claim. (Cl. 5—264)

My invention relates to bed springs, and has reference more particularly to the novel means of attaching the cross bars to the main frame.

In the attached drawing forming part of this application, Figure 1 is a fragmentary top plan of a spring embodying my invention.

Figure 2 is a fragmentary plan of the bottom of the spring unit, only the bottom frame being shown and the bars attached thereto; other parts being shown in dotted lines or entirely eliminated to better show the invention, and

Figure 3 is a vertical section on line 3—3, Figure 1.

Referring to the drawing, 5 is the main frame 15 in the shape of a rectangle, preferably made of angle iron, which at suitable intervals on its longer sides is provided with lugs 6 secured rigidly to the frame. Running transversely of the length of the frame 5 are cross bars 7, spaced so that 20 the flattened ends 8 of said bars will lie intermediate of the lugs 6.

To each flattened end 8 of the bar 7 is secured a yoke 9. The proximate ends of the yokes 9 and the lugs 6 are interconnected by tension springs 10, all of said springs normally lying in a plane parallel to the main frame 5 and acting 25 at substantially right angles to the bars 7. The bars 7, adjacent to the ends of the frame 5, have their yokes 9 connected to the frame directly by springs 10.

A secondary frame 13, also of a rectangular shape and made of angle iron, is positioned above the main frame 5 where it is supported by compression coil springs 11 and 12 carried by the 35 cross bars 7. At the very ends of the cross bars, only springs 11 are provided for the said cross bars are bent at the ends, as best shown in Figure 3. In other words, at the extremities of the cross bars 7, there is no room for springs 12, 40 so that at the longer side of the frame 5 compression springs 11 only are used.

Running intermediate of the springs 11 (see Figure 1), are strips 14 running transversely of the secondary frame 13, and strips 15 running longitudinally of said frame. In said Figure 1, only one coil spring 16 is fully shown in the corner; all the other springs are indicated by the upper loop of the coil spring so as to better illustrate the invention.

The overlapping parts of the strips 14 and 15 are united by clips 16 which serve also as anchors for tension springs 17, which unite the proximate top loops of coil springs 12 to said clips. Each end of the strips 14 and 15 are connected to the secondary frame 13 by a tension spring 18.

Any pressure applied to the strips, and in consequence, to the secondary frame 13, is transposed by the coil springs 11 and 12 to the cross bars 7, which, as previously described, are yieldingly attached to the main frame 5 by the tension springs 10. This connection permits the bars to float not only downwardly, that is to say, out of the plane in which said springs 10 are located, but also in the plane of the spring or substantially longitudinal thereof.

I claim:

In a bed spring, a main frame, bars running transversely of the main frame and having their ends substantially in the plane of the main frame while the main portion of said bars are below the plane of said frame, lugs extending from the frame intermediate of the bars, yokes provided on the end of the bars, tension springs lying in a plane substantially parallel to the frame and yokes, and running substantially parallel to the sides of the frame connecting the ends of the yokes to proximate lugs, a secondary frame, and cushion springs interposed between and operatively connected to the secondary frame and the bars.

ISIDORE ZIMET.
